METHOD OF SETTING TOWER FOOTINGS

Filed April 16, 1937

Technical drawings illustrating the assembly and components of a device, labeled Fig. 1 through Fig. 5.

Fig. 1. A perspective view of a device assembly. It features a vertical support structure with a top cap. A horizontal rod (3) is attached to the top cap, extending downwards. A small circular component (2) is attached to the end of rod (3). A vertical rod (10) is attached to the side of the support structure. A horizontal rod (11) is attached to the side of the support structure, extending downwards. A small circular component (5) is attached to the end of rod (11). A small circular component (8) is attached to the side of the support structure, positioned above rod (11). A small circular component (7) is attached to the side of the support structure, positioned above component (8).

Fig. 2. A side view of a long, horizontal, ribbed component. It has a central slot (9) and a ribbed section (10) on the right. A small circular component (13) is attached to the end of the ribbed section (10). A small circular component (11) is attached to the side of the component, positioned above the central slot (9). A small circular component (8) is attached to the side of the component, positioned above component (11). A small circular component (7) is attached to the side of the component, positioned above component (8). A small circular component (6) is attached to the side of the component, positioned below component (7).

Fig. 3. A detail view of a component labeled 14, showing a circular slot (15) and a ribbed section (14).

Fig. 4. A detail view of a component labeled 14, showing a circular slot (15) and a ribbed section (14).

Fig. 5. A detail view of a component labeled 14, showing a circular slot (15) and a ribbed section (14).

METHOD OF SETTING TOWER FOOTINGS

Myron A. Pithoud, Long Beach, Calif.

Application April 16, 1937, Serial No. 137,303

2 Claims. (Cl. 189—21)

This invention relates to the method of setting tower footings, whereby the various piers and the coupling member to which a leg of the tower is secured, are accurately set and spaced.

5 An object of my invention is to provide a novel method of setting tower footings which eliminates the use of large and cumbersome templets heretofore in use and which enable the contractor to quickly and effectively set the tower piers and the 10 coupling member in each pier in the proper positions.

Still another object is to provide a method of setting tower footings, whereby each footing can be set separately, thereby reducing the amount of 15 equipment necessary for excavation and setting.

An advantage of my method is that the tower footings can be set on rough contours where each footing is on a different elevation.

Still another advantage is the perfection in 20 setting each footing, all human errors being reduced to a minimum.

Other objects, advantages and features of invention may appear from the accompanying drawing, the subjoined detailed description and 25 the appended claims.

In the drawing:

Figure 1 is a diagrammatic plan view illustrating my method of setting tower footings.

Figure 2 is a fragmentary plan view of the adjusting jig.

Figure 3 is a fragmentary side elevation of the same.

Figure 4 is a top plan view of the calibrated plate.

35 Figure 5 is a side elevation of the same.

In setting the tower footings for structures such as power line towers and the like, the towers are spaced at fixed distances, these distances being determined by the engineer. The separate 40 piers are set either in a square or in a rectangle and where the power line passes through rough or mountainous country, the various piers are seldom at the same elevation.

45 Heretofore a square or rectangular templet has been used to determine the position of the four piers and also the position of the coupling member which is set in each of the piers. It is obvious in rough terrain, a great difficulty would be experienced in properly placing a long and cumbersome rectangular templet. My method and apparatus includes the following:

50 The central line of the transmission line is indicated at 1. By measuring along the line 1, a distance given on the engineer's map, it is possible

to accurately set the central point 2, over which the transit is positioned. The point 2 is the exact center of the square or rectangle formed by the four piers of the tower. When the transit is set on the point 2, a simple calculation will determine 5 the angle 3 and by turning this angle with the transit, the telescope will sight along the line 4 and will therefore bisect one corner angle of the square or rectangle. The distance along the line 4 can be calculated and thus the center of a pier 10 5 is actually determined. The other 3 piers are set in a like manner. It will be evident from the foregoing description that it is immaterial whether the piers are set at the same elevation or not. As long as a line can be sighted from the transit, 15 setting at the center of the rectangle to each of the footings, it is possible to accurately set each of the footings. Thus the footings can be set, one at a time, which is advantageous, particularly where water conditions are encountered and 20 it is necessary to pump out the excavation in order to set the concrete pier. Transmission towers are constructed of structural members and therefore a coupling member is embedded in the 25 concrete of each of the piers 5 and the legs of the tower are bolted to this coupling member. The coupling member shown at 6 must be accurately positioned in the pier so that the base of the tower will be a perfect rectangle. An adjusting jig 7 30 includes two longitudinally adjustable fittings each of which includes a tube 8, which is bolted or otherwise removably attached at 9 to the coupling member 6. A second tube 10 is attached to the tube 8 by means of the screw 11. The screw 11 is provided with left and right-hand threads 35 which screw into the tubes 8 and 10 respectively so that when the screw is rotated, the tubes will be adjusted longitudinally for the purpose of positioning the coupling members 6 as will be further 40 described. A pin 12 is driven through the hole 13 in the tube 10 and turns into the ground, thus anchoring the outer end of the tube. Plate 14 is bolted or otherwise removably attached to the coupling member 6 and this plate is calibrated 45 substantially as shown at 15 and by sighting through the telescope of the transit, the line 4 can be made to bisect the angle of the coupling member 6. The adjustment of the coupling member is accomplished by adjusting the screws 11 in 50 the two jigs at the direction of the man operating the transit. When the coupling member is in proper alignment and at a proper distance from the point 2, the concrete of the pier is allowed to set, thus fixing the coupling member. The other 55

three piers and coupling members are set in the same manner. The jig 7 is removed from the coupling member after it is set, and is then moved to the next pier where the operation as previously described is repeated.

Having described my invention, I claim:

1. An adjusting jig for setting tower footings, comprising a coupling member adapted to be fixedly mounted in a tower footing, a pair of bars 10 extending angularly from the coupling member, means securing each of the bars to the coupling member, means fixedly securing the outer end of each of the bars and means adapted to longitudinally adjust each of said bars, and a sighting 15 plate removably mounted on the coupling member, said plate having an indicating mark thereon

adapted to be aligned with an alidade mounted within the confines of the tower footing.

2. An adjusting jig for setting tower footings, comprising a coupling member adapted to be fixedly mounted in each tower footing, an adjusting 5 jig comprising a pair of arms extending angularly from the coupling member, means removably attaching the inner end of said arms to the coupling member, means fixedly securing the outer ends of the arms, each of said arms comprising 10 a pair of tubes, a screw threaded into said tubes, said screw being adapted and arranged to longitudinally adjust said tubes whereby the coupling member is adjusted, and a sighting plate removably attached to the coupling member. 15
